STORE DISPLAY

Claude W. Kress, New York, N. Y.

Application July 1, 1935, Serial No. 29,197

7 Claims. (Cl. 20—404)

My present invention relates to wall display fixtures, more especially of the type used in retail emporiums, for decorative display of merchandise both in the store and in show windows or cases. 5 An object of the invention is to provide a fixture of the above type, which may be selectively arranged at will for any of a wide variety of reflecting and opaque panel effects and with any of a wide variety of merchandise supporting and 10 display appurtenances, the entity in each relation being distinctly attractive and inviting.

Another object is to provide a fixture display of the above type, made up of slats, boards, channel bars, panels, moldings and other elements 15 which are relatively inexpensive, yet when assembled suggest elegance.

Another object is to provide a fixture of the above type, which lends itself readily for the almost instant application or removal of decorative panel covers, in accordance with the wish of the decorator without resort to adhesive, perforations or other mode of attachment apt to impair the capability of re-use. 20

Another object is to provide a fixture display installation of the above type, which in any and 25 all of its multifarious display settings, affords no hint of the fact that the installation has not been specially and permanently built for the particular layout in which it is embodied and bears 30 no conspicuous evidence of the purely structural props by which the display parts are removably held together.

Another object is to provide mechanical metal auxiliaries including channel bar uprights, shelf 35 brackets and spring cleats, each of which is inherently decorative in appearance and harmonizes with the general scheme of the design, the brackets and cleats being almost instantly yet securely applicable in any of a wide variety of 40 positions and being removable with substantially equal facility.

A feature of the invention is the arrangement of panels for the display, uprights, preferably metal channel bars intervening between the successive 45 panels and being preferably attached to corresponding slats against which the panels are held by horizontal moldings.

Another feature is the arrangement of slots in the channel bars, said slots depressed in a corresponding longitudinal groove therein, to render the same relatively inconspicuous and serving for removable attachment of shelf brackets and other parts to extend in front of the respective panels. 50

Another feature is the construction of shelf

bracket with a set screw directly accessible and exposed from the front of the buttress arm thereof and pressing against the panel strip to lock the conventional hooks of the bracket in position. 5

Another feature is the arrangement of spring pressed cleats latching selectively into any of the slots of the channel bar and serving removably to clamp any selected decorative cover in position over the panel. 10

In the accompanying drawings in which are shown one or more of various possible embodiments of the several features of the invention,

Fig. 1 is a front elevation of one illustrative embodiment of the invention. 15

Fig. 2 is a view in longitudinal cross-section with parts broken away taken on the line 2—2 of Fig. 1.

Fig. 3 is a view in longitudinal cross-section on a larger scale taken on the line 3—3 of Fig. 1. 20

Fig. 4 is a view similar to Fig. 3 taken on line 4—4 of Fig. 1.

Fig. 5 is a perspective view of a fragment of the channel bar upright,

Fig. 6 is a fragmentary view in transverse section on a larger scale taken on line 6—6 of Fig. 1, with parts broken away. 25

Fig. 7 is a fragmentary view on a still larger scale of the bracket structure and the mount thereof and shown on line 7—7 of Fig. 6, 30

Fig. 8 is a transverse sectional view taken on line 8—8 of Fig. 7.

Fig. 9 is a transverse sectional detail view taken on line 9—9 of Fig. 7.

Fig. 10 is a transverse sectional view on a greatly enlarged scale taken on line 10—10 of Fig. 1, and. 35

Fig. 11 is a transverse sectional view taken on line 11—11 of Fig. 10.

Referring now to the drawings, there is shown in Figs. 1 and 2, one of countless possible store or window fixture displays in which the invention may be embodied. The permanent part of said store display comprises a frame made up of a series of parallel, preferably uniformly spaced vertical slats 11 connected together at the lower ends by wooden boards 12 to which shelves 13 may

be attached, if desired, and connected together at their tops by cornice structure made up of board 14, and forwardly projecting horizontal board 15. 45

In a preferred embodiment, rigid uprights are attached to the respective slats 11 and serve for attachment of bracket shelves and the like. Preferably, these uprights are in the form of metal channel bars 16, and are secured to the 50

55

respective slats by wood screws 17. Preferably each channel bar has a longitudinal median groove 18 in its face in the plane of which groove, are lodged the heads of the attachment screws 17, which are disposed in the space between elongated longitudinal slots 19 at uniform intervals lengthwise of the channel bars, and of the width of groove 18.

Resting against the slats 11 and filling the space between successive channel bars 16, are panels 20 which, in a preferred embodiment are preferably of mirror glass backed by felt strips 21. These panels are secured in place by moldings 22 and 23 attached to the respective horizontal boards 13 and 15 and slightly in front of the respective boards 12 and 14.

The fixtures, of course, would be made up with panels in a variety of widths and heights and the numbers of panels would vary accordingly to the purpose of the fixture. Where a further decorative effect is desired, the fixture may be made with laterally offset bay panels 24—25 for instance, extending forward from the main fixture and flanking the latter.

The parts thus far described are the fixed elements of the fixture. The parts now to be described are the removable elements to be positioned as desired for the particular use or effect intended.

The longitudinal slots 19 as above set forth, serve for mounting of shelf brackets for the display in any of a variety of selected positions. Each bracket preferably includes an L-shaped stamping L having a conventional horizontal arm 26 with an upstanding toe at 27 and a heel at 28 for locating the glass or other shelf 29 therebetween.

The bracket also has a buttress portion 30 formed with two unitary downwardly extending hooks 31 and 32 which are adapted to pass through two of the slots 19 on the channel bar to rest on the lower edges of the latter, the two hooks being preferably spaced so as to expose the length of an intervening slot 19' in the channel therebetween. The bracket is locked in position preferably by means of a set screw 33 threaded into a tapped sleeve 34 rigidly retained in the buttress arm 30 of the shelf bracket and parallel to the shelf. For this purpose, the buttress arm of the shelf bracket may be bowed outwardly at 35 to lodge the length of the tapped sleeve which is latched in position by means of a complementary rigid strap 36, the ends or wings 37 of which extend through corresponding slots 38 in the bracket, and, if desired, may also be soldered or brazed in position. The set screw 33 has a knurled head 40 freely exposed in the angle of the L at the forward side of the buttress arm for convenience of access and manipulation. The position of the set screw is such that its reduced tip 41 preferably registers with the lower edge of the intervening slot 19' in the channel bar for correct positioning. Preferably a rigid metal washer 42 is firmly secured to the said reduced tip and pressed against the shoulder 43 determined by the end of the main portion of the set screw, so that when the set screw is tightened, said washer exerts substantial pressure against the channel bar and thereby retains the latching hooks 31 and 32 securely pressed against the under-face of the channel bar 16 and prevents any possibility of looseness.

The mounting of the bracket it is seen, in any of a variety of selected positions is practically the operation of an instant, the hooks 31 and 32

being merely placed in position and the set screw head is turned slightly until the parts are locked. The removal of the shelf bracket is just as easy and expeditious.

While the succession of mirror panels shown in the fixture may be effectively used, it is preferred for a variety of display, to cover selected ones of these mirror panels with colored panels usually fibre board or wood veneer board 45 decoratively covered as with corrugated paper 45', or any other ornamental facing to suit the wishes of the decorator. Thus, any of a wide variety of effects may be attained, such, for instance, as an opaque ornamental body flanked by mirrors or alternate panels of mirrors and corrugated paper, etc.

The present invention affords a convenient economical appliance for removably attaching the decorative cover over the selected panels. For that purpose, a horizontal molding strip 46 is preferably mounted adjacent molding 23 on the under piece of cornice board 15 and serves as shown, to retain the upper edge of cover board 45 in place. The lower parts of cover board 45 are releasably retained in place by one or more spring latch cleats snapped into one of the elongated slots 19 of the channel bar 16 and having wings overlapping the adjacent edges of the cover board.

A particular desirable construction of cleat latch is best shown in Figs. 10 and 11. It comprises a sheet metal strip bent into a U having a base 48, arms 49 and outturned wings 50. Superposed over the latter is a front plate 51 extending over the wings and preferably spot welded thereto. The latch comprises a hook 52 protruding through an aperture 53 in the base 48 and having a blunt extremity 54 protruding through the corresponding aperture 55 in the front plate. A metal washer 56 encircles the shank 57 of the hook, and is held in position by a cotter pin 58. A coil spring 59 encircles said shank and reacts at one end against the washer 56 and at the other against the base 48.

If desired as shown a decorative board 60 covered with corrugated paper or otherwise decorated might extend horizontally across the bottoms of the various panels as shown.

Among the multiplicity of various possible designs or effects in which the fixture may be embodied, Figs. 1 and 2 show illustratively the panels 62 and 63 covered by decorative corrugated board as shown, while all of the other panels 20 except that at the middle of the fixture are mirrors. Illustratively, the center of the fixture has a frame 64 mounted on shelf 13 and having casement windows 65 and curtains 66 in front thereof, to give the effect of a residence. This, of course, is merely illustrative. The shelves 29 in the present embodiment, illustratively are over those panels 62 and 63 covered with corrugated board, although it is quite obvious that the shelves might be arranged in any desired relation to extend over the mirror panels if desired in addition to or instead of the shelf arrangement illustratively shown.

In actual use, the longitudinal slots 19 in the channel bars 16 although shown in the drawings, are substantially invisible, blending with the shadow cast by the wall of groove 18 onto the bottom thereof, and this lends line and decorative effect to the display.

By the construction set forth, the store decorator can readily in a very short period and at frequent intervals completely re-arrange the disposition of exposed mirror and opaque panels

and the number and arrangement of shelves, to so radically alter the appearance as to create the impression that a completely new set of fixtures has been installed from time to time, lending variety and showing progressiveness of the establishment, which promotes customer appeal.

It will thus be seen that there is herein described apparatus in which the several features of this invention are embodied, and which apparatus in its action attains the various objects of the invention and is well suited to meet the requirements of practical use.

As many changes could be made in the above construction, and many apparently widely different embodiments of this invention could be made without departing from the scope thereof, it is intended that all matter contained in the above description or shown in the accompanying drawings shall be interpreted as illustrative and not in a limiting sense.

Having thus described my invention, what I claim as new and desire to secure by Letters Patent is:

1. As an article of manufacture, a spring clip comprising a U-shaped metal strip having a base, arms and laterally extending wings, a front plate rigidly secured to and across said wings, a latch hook having a shank through the front plate and the base of the strip and having an exposed hook conformation, a collar on said shank adjacent said front plate and a coil spring reacting at one end against said collar and at the other end against the base of said strip.

2. As an article of manufacture, a latch clip for the purpose described comprising a U-shaped metal strip having a base, arms and lateral wings, a front plate rigidly secured to and across said wings, a latch hook member extending through corresponding apertures in both the base of the strip and the front plate and having a hooked end exposed beyond said base, a metal washer about the shank, a cotter between the metal washer and the front plate and a coiled spring about said shank reacting at one end against the washer and at the other end against the base.

3. A wall fixture for decorative display of merchandise comprising a frame, mirror panels carried thereby against movement and extending in substantially a common plane, parallel rigid bars between successive panels and concealing the space between said latter panels, each of said bars being provided with a series of spaced conformations so formed as to receive brackets for supporting shelves in selective position along said bars, a decorative opaque panel covering at least

a portion of one of said mirror panels, and means connecting said opaque panel and one of said bars for releasably locking said opaque panel in position.

4. A wall fixture for decorative display of merchandise comprising a frame, mirror panels carried thereby against movement and extending in substantially a common plane, longitudinal channel bars inset and intervening between contiguous edges of said panels and laterally engaged by the latter, each of said channel bars having a series of bracket anchoring slots therein extending lengthwise of the bars, a decorative cover for one of said panels, and means anchored to one of said slots for retaining said cover in place.

5. A wall display comprising a frame, panels secured to said frame, longitudinal slotted metal channel bars between said panels and projecting outwardly therefrom, decorative covers over certain of said panels intervening between said bars and spring cleats extending over the edges of said decorative covers, each having a spring pressed hook extending inward therefrom and releasably anchored in a corresponding slot in the channel bar.

6. A wall display comprising a frame having spaced slats, rigid metal channel bars, screws therethrough attaching the same to said slats, a series of mirror panels intervening between the respective bars, decorative cover sheets over certain of said mirror panels, extending between neighboring channel bars and spring cleats removably securing said decorative covers in place, each of said cleats having wings overlapping the lateral edges of the corresponding cover or covers and having a spring pressed latching hook coacting with a corresponding slot in the channel bar.

7. A store fixture display comprising a frame including a plurality of vertical wooden slats, rigid metal channel bars extending lengthwise of said slats and secured thereto, mirror panels laterally contacting the flanks of the channel bars, each of said channel bars having a series of short, longitudinal slots midway of the exposed face thereof and adapted to receive brackets for supporting shelves, decorative covers removably superposed over certain of said mirror panels, and spring cleats removably securing the decorative covers in position, said spring cleats each having a spring pressed hook coacting with one of the slots in the corresponding channel bar, and having lateral wings overlapping the decorative panel or mirror panel as the case may be.

CLAUDE W. KRESS.
